UNITED STATES PATENT OFFICE

ERNEST JOSEPH BRASSEUR, OF CHICAGO, ILLINOIS, ASSIGNOR TO A. B. DICK COMPANY, OF CHICAGO, ILLINOIS, A CORPORATION OF ILLINOIS

STENCIL DUPLICATING MACHINE

Application filed March 22, 1928. Serial No. 263,885.

This invention relates to stencil-duplicating machines, and more particularly to means for registering the print on the work.

In an application for stencil-duplicating machines filed by me October 8, 1925, Serial No. 61,172, I have described a stencil-duplicating machine in which detent means associated with the printing cylinder, acts as a stop against which the cylinder may be rotated in reverse direction, so that the operator may place the cylinder in exactly the same relative position with respect to the leading edge of every sheet of work printed. The stop means referred to is not capable of adjustment, and therefore if the printing is placed a little too near or a little too far from the leading edge of the printed sheets, or not in correct registration with the lines of lined sheets, or with spaces thereon, it is necessary to adjust the stencil-sheet on the cylinder drum in order to bring the printing into the desired position on the printed sheets. Effecting such registration by removing and adjusting the stencil-sheet is a difficult and time-consuming operation, and usually results in the operator's hands becoming soiled with ink from the stencil-sheet and ink-pad.

The principal object of the present invention is to provide detent means for the counter rotation of the cylinder which is adjustable with respect to the cylinder so that the operator may correct or adjust the registration of the print on the printed sheets by merely adjusting the detent means and without being required to make any adjustment of the stencil-sheet on the impression-cylinder.

A further object of the invention is to provide print registration means of the character described which are simple in construction, positive and efficient in operation, and readily and easily adjustable.

Other objects of the invention will be in part obvious and in part pointed out hereinafter.

In order that a clearer understanding of my invention may be had, attention is directed to the accompanying drawings, forming a part of this application and illustrating the preferred embodiment of my invention,

and in which Fig. 1 is a side view of a rotary duplicating machine, showing the improved print registration means, a portion of the frame of the machine being broken away and certain parts being shown in dotted lines; Fig. 2 is a sectional view of the registration means and is taken on the line 2—2 of Fig. 1; and Fig. 3 is a perspective view of the cam action adjustment lever.

For the purposes of illustrating the application of the invention to rotary duplicating machines, I have shown the registration means applied to a rotary duplicating machine of the type disclosed in my said application. It is to be understood, however, that my invention may also be applied to rotary duplicating machines of other constructions.

As shown in the drawings, the duplicating machine comprises suitable frame-work 1, on which is journaled an impression-cylinder 2, having a shaft 3 and a hand-lever 4, whereby the impression-cylinder may be rotated in either direction.

The rubber impression-roller 5 is journaled on swinging arms 6, which are engaged by a cam-shaft 7, to the end of which is secured a hand-lever 8, whereby the cam-shaft 7 may be rotated to place the swinging arms 6 and the impression-roller 5 in raised position, in which the impression-roller is in printing contact with the impression-cylinder 2, or in lowered position, in which the impression-roller 5 is out of contact with the cylinder 2.

The shaft 3 of the impression-cylinder carries a collar 9, which has a notch 10, in which a spring-pressed pawl 11 is adapted to be received to stop rotation of the impression-cylinder 2 in the direction reverse to printing rotation. A pin-and-slot engagement between pawl 11 and the links 12 and 13 causes the pawl 11 to be withdrawn from the notch 10 whenever the handle 8 is swung to "off" position, thus releasing the cylinder 2 for counter-rotation, and at the same time the impression-roller 5 is held out of contact therewith, so that it cannot become smeared with ink from the impression-cylinder. The pin-and-slot connection between the link 12 and the pawl 11 permits the collar 9 to depress the

pawl 11 as the cylinder is rotated in printing direction.

In the machine shown in my said application, the pawl is mounted on a fixed pivot, and therefore the rotative position of the impression-cylinder when brought against the stop in counter-rotation cannot be varied. In accordance with the present invention, the pawl 11 is adjustable relatively to the collar 9 in such a way that the operator may set the pawl 11 to stop the counter rotation of the impression-roller in any one of a number of positions within certain limits.

To this end, the pawl 11 is provided with a circular aperture in which seats the hub 14 of a lever 15. Hub 14 is provided with an eccentrically located hole 16 and is pivotally mounted thereby on a stud 17 fixed in the frame of the machine. A screw 18 holds the hub in position on the stud.

It will be understood that rotation of the cam hub 14, by swinging lever 15 one way or the other, will move the end of the pawl 11 in a direction approximately tangential to the collar 9. Means are provided for locking the lever 15, and consequently the pawl 11, in adjusted position. As shown, such means comprises a screw 19 passed through the upper end of lever 15. Screw 19 is provided with a thumb-nut 20, and has an enlarged head 21, between which and the lever 15 is disposed a flange 22 formed on the upper edge of the enlarged fan-like tail 23 of the pawl 11.

A pin 24, carried on the pawl 11, engages in the slot 25 of the link-member 12. A spring 26, coiled about this pin and having one end 27 engaging the frame 1 of the machine, resiliently presses the end of pawl 11 against the collar 9.

Preferably, the circular edge of the tail 23 of the pawl 11 is graduated and the lever 15 is provided with a pointer 28 to indicate approximately the adjusted position of the pawl and consequently the approximate stopping position of the impression-cylinder.

In Fig. 1, there is shown in full lines the relative positions of the parts when the lever 15 is in such position that the impression-cylinder 2, when rotated in a direction reverse to printing direction, is stopped in its most forward rotative position. In dot and dash lines, in Fig. 1, are shown the relative positions of the parts when the lever 15 is in such position that the impression-cylinder on counter rotation is stopped in its extreme rearward rotative position. These two extreme positions of the impression-cylinder are indicated respectively on the drawing by the dash lines A and B. By adjusting the lever 15 to the proper intermediate position, the counter rotation of the impression-cylinder 2 may be stopped by the pawl 11 in any desired position between these extremes.

As will be apparent from the above de-

scription, it is a simple matter for the operator to make the adjustment which will position the print on the printed sheets in exactly the desired place thereon. If the operator finds that the print is not in correct registration on the printed sheet, either with respect to the leading edge of the sheet, or with respect to spaces on the sheet, or with respect to lines on sheets which are ruled or printed, he need only adjust the lever 15 so that when he brings the shoulder of the notch 10 in the collar 9 against the pawl 11, the impression-cylinder 2 will be in proper position to place the printing on the work in the proper place thereon.

When the operator has adjusted the pawl 11 in accordance with the registration desired, every sheet printed thereafter will receive the printing in exactly the same registration, provided the operator is careful to bring the shoulder of the notch 10 in collar 9 against the end of the pawl 11 each time before he rotates the impression-cylinder 2 in printing direction, assuming, of course, that each sheet is properly inserted into engagement between the impression-cylinder and the rubber roller 5.

It will be readily apparent from the construction disclosed that proper registration of printing on sheets may be secured in a most simple and easy manner without requiring the stencil sheet to be adjusted on the impression-cylinder.

As many changes could be made in the above construction and as many apparently widely different embodiments of this invention could be made without departing from the scope thereof, it is intended that all matter contained in the above description or shown in the accompanying drawings shall be interpreted as illustrative and not in a limiting sense.

What I claim is:

1. In an apparatus of the character described, in combination, a rotatable cylinder and means for limiting rotation of the cylinder in a certain direction, said means including an element rotatable with the cylinder, and a coacting stop pawl mounted on a shiftable pivot, and means, including a finger grip element, for adjusting the position of said shiftable pivot to vary the rotative stop position of the cylinder.

2. In an apparatus of the character described, in combination, a rotatable cylinder, means for limiting rotation of the cylinder in a certain direction, said means including an element rotatable with the cylinder, and a coacting stop pawl mounted on a shiftable pivot, means, including a finger grip element, for adjusting the position of said shiftable pivot to vary the rotative stop position of the cylinder, and means controlled through said finger piece for locking said pivot in adjusted position.

3. In an apparatus of the character described, in combination, a rotatable cylinder and means for limiting rotation of the cylinder in a certain direction, said means including an element rotatable with the cylinder, an eccentrically mounted member and a pawl pivotally carried on said eccentrically mounted member, and means, including a finger grip element, for adjusting the position 10 of the eccentrically mounted member to vary the rotative stop position of the cylinder.

4. In an apparatus of the character described, in combination, a frame, a cylinder rotatable on the frame, a notched element rotatable with the cylinder, a hub mounted for eccentric rotation on said frame, a stop pawl pivotally mounted on said hub and coacting with said notched element, whereby rotation of said hub on the frame shifts said pawl 15 bodily with respect to said notched element, and means, including an adjustable lever, whereby said hub may be rotated to vary the rotative position of the cylinder when the notched element is rotated into engagement 20 with said pawl.

5. In an apparatus of the character described, in combination, a frame, a cylinder rotatable on the frame, a notched element rotatable with the cylinder, a hub mounted 30 for eccentric rotation on said frame, a stop pawl pivotally mounted on said hub and coacting with said notched element, whereby rotation of said hub on the frame shifts said pawl bodily with respect to said notched element, 35 means, including an adjustable lever, whereby said hub may be rotated to vary the rotative position of the cylinder when the notched element is rotated into engagement with said pawl, and means for locking said 40 lever in adjusted position.

6. In an apparatus of the character described, in combination, a frame, a cylinder rotatable on the frame, a notched element rotatable with the cylinder, a hub mounted for eccentric rotation on said frame, a stop pawl pivotally mounted on said hub and coacting with said notched element whereby rotation of said hub on the frame shifts said pawl bodily with respect to said notched element, 45 means, including an adjustable lever, whereby said hub may be rotated to vary the rotative position of the cylinder when the notched element is rotated into engagement with said pawl, said pawl having an enlarged tail portion, and means for locking said lever to said tail portion, whereby said lever is held in 50 adjusted position.

7. In an apparatus of the character described, in combination, a frame, a cylinder rotatable on the frame, a notched element rotatable with the cylinder, a hub mounted for eccentric rotation on said frame, a stop pawl pivotally mounted on said hub and coacting with said notched element, whereby 60 rotation of said hub on the frame shifts said

pawl bodily with respect to said notched element, means, including an adjustable lever, whereby said hub may be rotated to vary the rotative position of the cylinder when the notched element is rotated into engagement 70 with said pawl, said pawl having an enlarged tail portion, and means for locking said lever to said tail portion, whereby said lever is held in adjusted position, said tail portion being graduated and said lever having a co-acting pointer for indicating the adjusted position of said stop pawl relatively to the notched element and cylinder.

8. In an apparatus of the character described, in combination, a frame, a rotatable cylinder, a cylinder shaft, a stop member carried on said shaft for rotation therewith and having a stop portion, an eccentrically rotatable pivot mounted on the frame, a pawl rotatably mounted on said pivot and adapted 80 to coact with said stop member to stop the cylinder upon rotation in a certain direction, in a predetermined position, and means for rotating the eccentrically rotatable pivot to adjust the pawl relatively with respect to 85 the stop member to vary the predetermined stop position of the cylinder.
